ABSTRACT OF THE DISCLOSURE

For developing latent electrostatic images on paper sheets there is provided a developing station which includes a tank for holding a bath of liquid developer including an insulating carrier liquid with pigment particles dispersed therein, and a restricted guideway or channel for leading the sheets down into and up out of the bath. The upper member, at least, of the guideway is of conductive material and provides a field control effect for intensifying the deposit of pigment particles in the image areas. The field control member must be placed close to but out of contact with the imaged sheet surface in order to have the desired field control effect. In order to replace the liquid developer in this restricted channel rapidly enough to prevent its being stripped of pigment particles, the field control member is provided with openings through which fresh liquid developer can be rapidly introduced into the channel, and spray means and baffles are arranged to effect this developer replacement as efficiently and rapidly as possible. Moreover, the arrangement is such that hydrodynamic forces are also generated in the liquid developer in the channel to maintain the sheet against a guiding surface and hence at an accurate spacing from the field control member.

This application is a continuation of application Ser. No. 763,606, filed Sept. 30, 1968, now abandoned, which is a continuation of application Ser. No. 561,784, filed June 30, 1966, now abandoned.

This invention relates to the deposition of particles upon the surface of a moving sheet in accordance with a latent electrostatic pattern previously formed thereon, and especially in situations where it is desirable to employ a liquid as the carrier for the particles during deposition.

The treating of an electrostatically imaged sheet with a liquid developer having electrostatically attractable particles dispersed therein is a well-known procedure and is frequently carried out by immersing the sheet in a bath of the developer.

The present invention is based upon the principle that improved deposition can be obtained by means of a conductive field control member placed very close to, but accurately spaced from, the surface of the sheet to be developed, and embodies a means for maintaining an accurate minimum spacing relationship between such a field control member and the sheet surface under the relatively unstable circumstances represented in progressive appli-

2

cation of developing liquid to the electrostatic image on a sheet moving through a developer bath. However, in a broader sense, the invention also involves the maintenance of accurate spacing between these surfaces in a kinetic electrostatic development situation whether or not the process relates to immersion development or to some other type.

It may be noted at this point that a conductive field control member, placed close to the photoconductive surface during development not only speeds deposit but also assists in providing a uniform deposit over large solid areas and avoids edge effects. By "edge effects" is meant the electrical field phenomenon which results in a low intensity deposit found in the centers of large charged areas, which are intended to show a solid, uniform density when developed, but instead display dark edges shading to grey to white centers.

This invention, in the presently preferred form provides a guide channel for a sheet to be developed and through which the sheet is fed and from which it is withdrawn by feed rollers. The channel is arranged to expose the sheet to a bath of liquid developer, and this is brought about in the form shown by positioning the channel to dip into a bath of developer which is maintained at a predetermined depth. One member making up the channel is a guide member against which the sheet rests and the other member is a conductive member placed in fixed closely spaced relation to the guide member so as to provide a field control effect at the place where electrostatic deposit of particles is occurring. The sheet is held against the guide member by hydrodynamic forces generated in the liquid itself so as to provide consistent accurate spacing between the surface of the sheet and the field control member. Preferably these hydrodynamic forces are generated by pumping or flowing the developing liquid rapidly through orifices in the field control member so as to hold the sheet strongly away from the field control member and against its locating guide member as it passes through the developing zone.

In the drawing:

FIG. 1 is a schematic section of one form of device for developing an electrostatically imaged sheet by treatment with a liquid developer in accordance with the present invention; and

FIG. 2 is a detail section consisting of a portion of FIG. 1 drawn to an enlarged scale.

Referring to the drawing, there is illustrated therein a tank 10 containing a bath 12 of liquid developer of the type designed for use with electrostatic deposition procedures, and having dispersed therein minute electroscopic particles which will deposit upon electrostatically charged areas of a sheet surface. A sheet 14 provided with a latent electrostatic image on its upper surface is led down into and then up out of the bath 12 by an assembly 16 which provides a channel 18 within which the sheet is confined. The assembly 16 comprises lower or guide plate 20 and an upper or field control plate or member 22 which is made of metal or other electrically conductive material spaced uniformly and accurately from the surface of the guide plate 20.

Means in the form of rollers 24, 26 and 28, 30 perform the functions respectively of introducing the sheet

14 into the channel 18 and withdrawing it therefrom. The latter pair, i.e. rollers 28, 30, also preferably perform a squeegee operation on the sheet to remove excess liquid therefrom and return the same to the bath 12.

In order to maintain an appropriate liquid level in the bath 12 and to keep the liquid developer properly mixed and agitated, there is provided a reservoir 32 which has a supply of liquid developer therein and which houses a pump 34 driven by a motor 36. The pump moves the liquid developer through a discharge conduit 38 to a manifold 40 extending across the top of the bath 12 transversely of the direction of sheet movement. The manifold has a plurality of openings along its length, one of which is indicated at 42. These openings are downwardly directed so that the liquid developer which is under the pressure in the manifold 40 is sprayed or flowed forcibly downwardly against the upper surface of the field control member 22 as indicated at 43. The field control member is provided with apertures 44 some of which are arranged in the path of the spray 43 so as to admit the spray to the channel 18 and against the upper surface of the sheet 14 from whence it escapes to the bath 12 through the open sides of the channel. In the preferred arrangement, louvers or baffles 46 are struck up from the plate 22 adjacent the apertures 44 to assist in guiding the spray in the desired direction.

An overflow pipe 48 determines the proper level for liquid in the bath 12 and returns any excess to the reservoir 32.

In FIG. 2 it can be seen that there is a predetermined spacing S between the top surface of the guide plate 20 and the bottom surface of field control plate 22, due to their common center curvature and fixed mounting relationship. There is likewise a spacing S' between the sheet surface and the field control plate 22 which under normal circumstances will vary due to the dynamic conditions of liquid development. In order to provide the desired field control effect as a result of the conductive nature of the plate 22, this spacing S' must be quite small and must be maintained constant with a certain degree of accuracy. A distance of about $\frac{1}{2}$ inch has been found about the optimum in practice with paper sheets of usual thickness and electrical properties, and a range of spacing of about $\frac{1}{64}$ inch to $\frac{1}{8}$ inch is found to be the range of effective field control values. For convenience, spacing within the general ranges identified may be referred to as effective field control spacing. As the spacing S is made small for effective field control, local random variation in S' becomes of even greater importance. For example, a variation of $\pm .005$ inch in S' if $S = \frac{1}{64}$ is highly undesirable whereas if $S = \frac{1}{8}$ inch the same fluctuation in S' would create virtually no visible differences in the developed image.

To minimize local random variations it is desirable to cause the sheet to conform very closely to the guide member so that the precision attainable in the mounting of the plates 20 and 22 will be effective to minimize variations in S', and this is admirably achieved according to this invention by the hydrodynamic action of the liquid developer itself in that the hydrodynamic pressure of the liquid in spray 43 is exerted against the surface of a sheet 18 to hold it against the surface of the guide plate 20.

The use of the hydrodynamic action of the developing liquid to maintain the surface of the electrostatically imaged sheet against a guide which insures accurate spacing from the surface of the conductive field control plate 22, makes it possible to employ a field control technique on a practical basis with very close spacing of the field control member, and thereby produce imaging of the highest quality. It is, moreover, possible to accomplish these results in such a way that the need for complex means for assuring proper positioning and adequately close tolerances of spacing of the sheet across its whole surface is avoided. The hydrodynamic effect of the de-

veloping liquid acts automatically and simultaneously at all points on the sheet which are in the developing zone by reason of being exposed to the liquid.

In certain respects the field control aspect of the equipment assists development, while in other respects it has been found to inhibit it. In general the closer the field control conductor is placed to the photoconductive surface the more rapidly the electroscopic particles are deposited on the charged areas of the sheet. When very close spacing is involved, however, this deposit can be so rapid that the small amount of developer liquid available in the area between the closely spaced surfaces tends to become stripped of particles so that subsequent image areas are starved and do not receive appropriate deposits if the sheet moves through the bath at normal copier speeds. This effect is aggravated to some extent by the fact that changing the liquid adjacent the sheet surface necessarily becomes more difficult the closer the sheet surface is brought to the field control conductor since there is a smaller cross sectional area available through which fresh liquid can be introduced.

Due to the relationships stated in the foregoing paragraph it is important, especially when the closer spacings are used, to purposefully move the liquid developer in a manner that insures adequate rapid replacement to prevent the starvation phenomenon alluded to. In the presently disclosed form of the invention, the forceful spraying of the liquid developer is at sufficient velocity, and the liquid is introduced into the channel 18 at a number of points which are close enough together so that there is fairly rapid movement of the liquid between the plates 20 and 22. Accordingly, the developer liquid in the channel 18 is sufficiently energized as to move parallel to the sheet surface with a speed sufficient to insure that any stripped developer rapidly escapes from the channel 18, and the channel is continually flooded with fresh developer liquid so that rapid exchange of fresh particle-charged developer for stripped developer is assured. Thus a sheet 14 may be moved through the channel at a speed acceptable for commercial copier use without exhibiting deficient development in the trailing portions of the image.

While only the field control plate 22 has been referred to as conductive, it is found beneficial in some instances to actually apply a voltage across the gap between the field control plate and the surface of the sheet, in which case the guide plate 20 is also made conductive and a source of EMF is connected both to the plate 22 and to the guide plate 20.

It will be understood that various configurations and structural arrangements may be provided, and that the invention consists essentially in a development process and apparatus which involves the use of a fluid medium wherein dynamic forces are generated within the fluid medium itself, acting upon the sheet to hold it against a guide surface appropriately adjacent to but spaced from a conductive field control member, the spacing being at an effective field control value. For example, while the present invention shows spraying the liquid from the manifold 40 upon the upper surface of the field control member 22, it will be appreciated that with proper spacing and conductivity, the manifold 40 could serve as the field control member if desired.

While a preferred embodiment of the invention has been described and illustrated, it is to be understood that this is capable of variation and modification. Accordingly, the aim in the appended claims is to cover all such variations and modifications as may fall within the true spirit of the invention.

What is claimed is:

1. A method of developing electrostatic latent images on sheet surfaces which comprises:
positioning an apertured electrically conductive field control member and a guide member in close relationship with a gap between them defining an effective field control spacing;

passing a sheet, whose surface has been electrostatically imaged, between said guide member and field control member with the imaged surface towards said field control member;

while passing said sheet between said member, flooding the portion of the gap between said field control member and said sheet with an electrostatic developer fluid containing particles electrically attractive to areas on the surface of the sheet; and

forcing fluid developer through an aperture in the field control member and against the sheet to thereby generate dynamic forces in the fluid developer entering the gap in a direction and of a magnitude to hold the sheet consistently away from the field control member and against the guide member during passage of the sheet between said members.

2. A method of developing electrostatic latent images on sheet surfaces which comprises:

positioning an apertured electrically conductive field control member and a guide member in close relationship with a gap between them defining an effective field control spacing;

passing a sheet, whose surface has been electrostatically imaged, between said guide member and field control member with the imaged surface towards said field control member;

while passing said sheet between said members, flooding the portion of the gap between said field control member and said sheet with an electrostatic developer fluid containing particles electrically attractive to areas on the surface of the sheet by forcing fresh developer fluid through an aperture in said field control member and against the sheet to generate dynamic forces in the fluid developer entering the gap in a direction and of a magnitude to hold the sheet consistently away from the field control member and against the guide member during passage of the sheet between said member; and

causing such fresh fluid to be projected rapidly through the aperture into the gap with a direction of motion having a substantial component parallel to the surface of the sheet so as to bring about fluid motion within the gap parallel to the surface of the sheet to continually displace fluid in the gap from which the particles have been electrostatically removed by preceding portions of the moving sheet, and to replace it with the incoming fresh fluid rapidly enough to prevent nonuniform development due to stripping of the developer available to the sheet surface.

3. A device for developing electrostatic latent images comprising:

a guide member;
an apertured electrically conductive field control member;

means mounting said members in close relationship with a gap therebetween defining an effective field control spacing;

means for feeding a sheet whose surface has been electrostatically imaged through said gap with the imaged surface towards the field control member;

means for introducing into the portion of the gap between said field control member and a sheet being fed through the gap an electrostatic developer fluid containing particles electrically attractive to the image on the sheet; and

means for generating dynamic forces in the fluid developer entering between said sheet and field control member in a direction and of a magnitude to hold a sheet consistently away from the field control member and against the guide member during its passage between said members, said last-named means comprising equipment for moving developer fluid through an aperture in the field control member and against the imaged surface of the sheet.

4. Means for developing an electrophotographic sheet having a latent electrostatic image on one surface comprising:

a tank for containing a bath of liquid developer including electroscopic pigment particles dispersed therein;

guide means associated with said tank and defining a path for said sheet down into and up out of said bath of liquid developer;

a conductive field control member parallelling the path of the sheet through the developer at the side thereof bearing the electrostatic image and arranged sufficiently closely to the path as determined by said guide means to provide an effective field control spacing with relation to the surface of a sheet traveling in said path;

means for moving a sheet through said path; and means for maintaining said sheet out of rubbing contact with the surface of the field control member as it moves through said path.

5. For developing an electrostatic image on a sheet of material, apparatus comprising:

a container for a pool of developer;
means for guiding the sheet through the pool along a predetermined path which dips into the pool with the image side of the sheet facing upwardly;
a perforate metallic member in the pool juxtaposed to the upper side of the path and arranged sufficiently closely to the path to provide an effective field control spacing with relation to the surface of a sheet travelling in said path; and

means for forcibly projecting developer through openings in said perforate member with a force and direction sufficient to maintain the upper sheet surface spaced away from the perforate member on its passage through the pool.

6. For developing an electrostatic image on a sheet of material, apparatus comprising:

a guide member for guiding a sheet along a development path;

a perforate conductive member arranged adjacent the guide member and having a generally matching configuration, said members being arranged with a gap between them defining an effective field control spacing, and mutually forming a channel for the sheet; means for moving the sheet along the path through said channel with its imaged surface faced towards said perforate conductive member.

means for forcibly projecting liquid developer through the openings in said perforate member with a force and direction sufficient to maintain a body of developer in said channel between the imaged surface of a sheet being processed and the adjacent surface of said conductive member, and to continually displace the said body of developer and replace it with the incoming developer rapidly enough to avoid starvation effects.

7. A developing device as set forth in claim 6 which further includes means for forcibly projecting liquid developer through the openings in said perforate member with a force and direction sufficient to hold the sheet spaced from said conductive member and against said other member during development.

8. For developing electrostatic images on a sheet of material, apparatus comprising a container for a pool of developer, means for guiding the sheet through the pool along a predetermined path which dips into the pool with the image side of the sheet facing upwardly, upper and lower metallic members in the pool juxtaposed to the upper and lower sides of the path respectively, the upper member being perforate, and means for flowing developer downwardly through the perforate member to the image side of the sheet.
